UNITED STATES PATENT OFFICE.

PYRMA E. FISCHER, OF NEW YORK, N. Y.

ROTATABLE SOAP-HOLDER.

1,107,278.

Specification of Letters Patent. Patented Aug. 18, 1914.

Application filed July 8, 1913. Serial No. 777,878.

To all whom it may concern:

Be it known that I, PYRMA E. FISCHER, a citizen of the United States, residing in the city of New York and State of New York, 5 have invented a new and useful Improvement in Rotatable Soap-Holders, of which the following is a specification.

This invention relates to a device for producing a continuous flow of soapy water and 10 is especially adapted for use in washing dishes, or clothes where water can be had under pressure, as in houses connected with a street main.

The invention consists of the novel features of construction hereinafter described, 15 pointed out in the claims and shown in the accompanying drawings, in which,

Figure 1 is a vertical section a soap holder being in elevation. Fig. 2 is a similar section at right angles to Fig. 1. Fig. 3 is a horizontal section, the soap holder being shown in top plan.

In constructing the device, I employ a spherical casing comprising the lower portion 25 1 and an upper and smaller top portion 2 which is preferably threaded to the lower and larger portion, but which may be secured to the portion 1 in any manner which forms a tight joint and permits ready separation of the two sections. The upper or top section 2 carries a coupling 3 adapted to be threaded upon an ordinary water spigot and the section 1 carries a discharge nozzle 4 upon which is adapted to be fitted a piece 30 of flexible hose 5 through which the water is conveyed to the place of use. A transverse shaft 6 is carried by the section 1, and is off-set with respect to the center of said section thereby placing said shaft out of 40 vertical alinement with the water inlet through the coupling 3 and the discharge through the nozzle 4; said shaft is provided with fixed collars 7. Loosely hung upon the shaft between said collars is a reticulated 45 soap container 8 provided with a suitable cap or end piece 9. This I have shown as hinged but it may be secured to the receptacle in any desired manner. This receptacle is adapted to contain soap in either large or 50 small pieces, or if desired the receptacle can be made of a sufficiently fine mesh to adapt it to contain any of the washing powders now found upon the market.

In operation the water discharged through the coupling 3 strikes the receptacle 8, and 55 as said receptacle is hung upon the shaft off-set with respect to the point of admission of the stream of water and as said stream, under pressure of the street mains, or under pressure derived from an overhead tank or 60 other form of water system, strikes the soap container it will cause the same to revolve about the shaft within the casing. This will cause rapid saponification and the water will issue from the casing 1 in a soapy condition, and it will be obvious that the device may be attached to either a hot or cold water source of supply. In washing dishes this provides an immediate supply of clean soapy water which is continuously renewed during 70 the washing operation, and avoids placing the soap in the dish water or handling the same with the hands.

This device is especially adapted for use in a dish washer which forms the subject 75 matter of a separate application.

What I claim is:—

1. A casing having a water inlet and a discharge outlet upon opposite sides, a shaft off-set with respect to said inlet and discharge openings, and a soap container rotatably mounted upon said shaft.

2. A device of the kind described comprising a casing adapted to receive water from a spigot and having a discharge opening in vertical alinement with said spigot, a shaft off-set with respect to the point of admission of the water, and a soap retainer loosely mounted upon said shaft and extending into the path of discharge of water from 90 the spigot into the casing.

3. A device of the kind described comprising a sectional casing having a detachable top portion, means carried by the top portion for securing the casing to a spigot, 95 a discharge nozzle carried by the other portion, a shaft arranged horizontally and to one side of the center of the casing and a reticulated soap container loosely hung upon the shaft, as and for the purpose set forth. 100

PYRMA E. FISCHER.
